A. C. ROWLEY

AUTOMATIC SPRINKLER

Filed April 26, 1923

Inventor.—
Arthur C. Rowley.
By his Attorneys.—
Hanson & Hanson

UNITED STATES PATENT OFFICE.

ARTHUR C. ROWLEY, OF PHILADELPHIA, PENNSYLVANIA, ASSIGNOR TO GLOBE AUTOMATIC SPRINKLER COMPANY, OF PHILADELPHIA, PENNSYLVANIA, A CORPORATION OF PENNSYLVANIA.

AUTOMATIC SPRINKLER.

Application filed April 26, 1923. Serial No. 634,901.

To all whom it may concern:

Be it known that I, ARTHUR C. ROWLEY, a citizen of the United States, residing in Philadelphia, Pennsylvania, have invented 5 an Automatic Sprinkler, of which the following is a specification.

One object of this invention is to provide a relatively simple and efficient form of sprinkler head which while possessing all the 10 advantages inherent in both the lever and diaphragm types of heads, shall be free of their objectional features, and the invention more especially contemplates the provision of a sprinkler head which shall be compact, 15 substantial and certain in action, and which shall include such an arrangement of parts that when subjected to a predetermined temperature, it will certainly separate into its several pieces so as to release its valve and 20 permit delivery of water.

Another object of my invention is to provide a novel form of fusible- or temperature-responsive link of the compression type which shall include novel means for insuring the complete and instantaneous separation of its elements when these are subjected to more than a predetermined degree 25 of heat.

These objects and other advantageous ends 30 I attain as hereinafter set forth, reference being had to the accompanying drawings, in which,

Fig. 1 is a front elevation of a sprinkler head embodying my invention;

Fig. 2 is a vertical section on the line 2—2, Fig. 1;

Fig. 3 is a vertical section on a larger scale than Fig. 2, illustrating in detail the construction and arrangement of parts of 40 the fusible link forming part of my invention;

Figs. 4 and 5 are perspective views of the two main plates of my fusible link;

Fig. 6 is a perspective view of the plate-controlling key;

Fig. 7 is a perspective view of the key-controlling element;

Fig. 8 is a perspective view of the spring; and,

50 Figs. 9 and 10 are perspective views respectively of the valve and valve washer used for normally closing the outlet of my sprinkler head.

In the above drawings, 1 represents a

threaded nipple having an outlet designed 55 for the reception of a washer 2, with a valve 3 and having integral yoke 4. The latter in the center line of the nipple 1 has threaded into it a screw 5 carrying a water spreader 6 and designed to have confined between its 60 inner end and the valve a fusible link hereinafter described.

In accordance with my invention, this link includes a pair of substantially flat parallel plates 7 and 8, of which the latter has its upper end 9 over-hung and preferably provided with a depression 10 for the reception for the suitably formed inner end of the screw 5. The upper end of the plate 7 is preferably formed with a somewhat sharpened edge designed to fit under the overhanging portion 9 in the plate 8, so as to engage the same between its face and a line drawn parallel with said face through the center of the recess 10. 75

Between the top face of the valve 3 and lower end of the plate 7, I mount a U-shaped spring 11 the ends of whose arms are preferably formed with notches or recesses 12 for the reception of lateral extensions 13 constituting trunnions at the ends of the top edge of the plate 7. For suitably positioning the plate 7 and spring 11 on the valve 3, the lower end of said plate preferably has a projection 14, while the center of the bottom 80 of the spring 11 is provided with a recess 15 for said projection, the middle of said spring being projected in line with said recess to enter a depression 16 in the center of the top face of the valve 3. 85

The plates 7 and 8 are formed with longitudinally extending aligned slots respectively indicated at 17 and 18 for the reception of a flat key 19 and said slots are of such dimensions and are relatively so placed 95 that their lower ends are at different levels or are out of alignment as shown in Fig. 3. The lower edge of the key 19 is preferably stepped or offset as indicated at 20 so that its flat surfaces lie parallel with and so engage the flat ends of the slots that a swinging movement of the key out of said slots is impossible without a corresponding upward movement of said key longitudinally of the slots. 100

For normally preventing or resisting such an upward movement of the key in the slots 17 and 18, I transversely recess the adjacent 105

faces of the plates 7 and 8 for the reception of a key-controlling element in the form of a roller 21 (Fig. 7) so mounted as to intersect the upper portions of the slots 17 and 18 5 and lie within a notch 22 in the top edge of the key 19.

As will be understood by those skilled in the art, the two plates 7 and 8 with the key 19 and key-controlling element 21 are 10 all sweated or soldered together with a suitable metal or alloy of such composition as to fuse when heated to a relatively low degree, for example 165° F. Under normal conditions, however, this metal firmly binds 15 together in parallel relation the two plates 7 and 8, maintains the element 21 in position between said plates and coacts with said element in holding the key 19 in the position shown in Fig. 3 so that it cannot 20 move out of the slots of said plates. This fusible link formed by these four members may be introduced between the spring 11 and the inner, or pointed end of the screw 5, and the trunnions 13 of its plate 7 are 25 caused to enter the notches 12 of the arms of the spring, while said screw is set up so that its inner end enters the depression 10 of the plate 8 and places said spring under compression by bowing it, as the projecting lower end 14 of the plate 7 is forced 30 into the depression 15 of said spring. The latter, as previously indicated and as shown in Fig. 3, is seated centrally of the top of the valve 3, and is noted that its arms with 35 the two plates 7 and 8 lie in or parallel with the plane of the yoke 4. While the key 19 extends transversely of this plane, it projects but little if any beyond the planes defined by the side edges of the spring. 40 Obviously when the parts are assembled as above described, not only the spring 11 but also the fusible link as a whole is under stress. At the same time the various parts under normal conditions retain their given 45 relative positions against air or water pressure exerted upon the valve 3 from the piping system to which the nipple 1 is connected. If, however, the temperature of the fusible link or of the atmosphere in its 50 vicinity rises above 165° or exceeds whatever other temperature is required to fuse the metal connecting the parts of said link, the plate 8 fulcrums on the top edge of the plate 7, when the fusible metal connecting 55 it with said second plate is melted. The outward swinging of said plate 8, while normally prevented by the key 19, is now possible since the melting of the fusible metal allows the key-controlling element 21 to move or be forced upwardly between 60 the plates 7 and 8, by reason of the force exerted upon it by the key 19, which tends to move upward owing to the tendency of the plates 7 and 8 to separate. The separation 65 of the plates 7 and 8 is still further

accelerated and is made certain by the action of the spring 11, which is now free to forcibly move the plate 7 upon whose trunnions 13 it acts so that this is raised away from the valve. As a consequence of the above action, 70 the fusing of the metal connecting the parts of the link results in what is practically an instantaneous and forcible separation of the parts of the latter and the unseating of the valve 3 with its washer 2, so that air or water under pressure within the system of which the sprinkler forms a part, is allowed to escape through the nipple 1. By reason of the above noted forcible separation of the parts of the fusible link there is no 75 possibility of their being held in a partially released or separated position by reason of the sudden cooling of the fusible metal by water escaping from the nipple, since the construction of the parts of the link as well as the spring 11 insures the certain and rapid action of the sprinkler head whenever and as soon as the temperature in its vicinity rises to or above the predetermined 80 point. 90

I claim—

1. A fusible link comprising two plates; a key extending through said plates; a controlling element mounted between the plates to normally prevent movement of the key; and fusible material binding together said plates, key, and controlling element. 95

2. A fusible link comprising two plates fulcrumed one upon the other; a controlling element in the form of a plate extending 100 in a plane at right angles to said first mentioned plate; and a key normally held by said element in position to prevent relative movement of the plates; with relatively fusible material normally binding said parts 105 together.

3. A fusible link comprising two slotted plates; a key extending through the slots of said plates; an element between the plates normally engaging the key to hold it in 110 position to prevent relative movement of the plates; and relatively fusible material separably connecting said parts.

4. A fusible link comprising two plates; a key having a stepped portion engaging the plates; an element normally holding the key with its stepped portion in position to prevent movement of the plates; and fusible material separably connecting the plates. 115

5. A fusible link comprising two plates; a key having a stepped portion engaging the plates; an elongated element between the plates normally preventing movement of the key; and fusible material separably connecting said parts. 120

6. A fusible link consisting of two plates of which one has an overhung portion and the other a relatively sharp edge engaging said portion; an elongated element mounted between the plates; and a key extending 125 130

through the plates and normally maintained by said element in position to prevent their relative movement; with relatively fusible material separably connecting the plates, key and element.

7. The combination in a fusible link of two slotted links fulcrumed one on the other; a key extending through the slots of said plates and having an edge portion engaging adjacent ends of said slots to normally prevent relative movement of the plates; an elongated member mounted between the plates and positioned to normally prevent movement of the key; and fusible material separably connecting said parts.

8. The combination in a sprinkler head of a nipple; a yoke; a valve normally closing the outlet of said nipple; a fusible link having trunnions; and a spring engaging said trunnions and confined with said fusible link between the valve and the yoke.

9. The combination in a sprinkler head of a nipple; a yoke; a valve normally closing

the outlet of said nipple; a fusible link having trunnions; and spring operative on the trunnions of the fusible link tending to release the valve.

10. The combination in a sprinkler head of a nipple; a yoke; a valve closing the outlet of the nipple; a U-shaped spring operative on the valve; with a fusible link confined between the yoke and the spring and including trunnions engaged by the arms of said spring.

11. The combination in a sprinkler head of a nipple; a yoke; a valve normally closing the outlet of the nipple; U-shaped spring mounted on the valve; a fusible link confined between the yoke and the spring and including projecting portions acted on by the spring, said link comprising two parallel plates fulcrumed one upon the other; a key normally preventing relative movement of the plates; and fusible material normally binding together said key and plates.

ARTHUR C. ROWLEY.
